UNITED STATES PATENT OFFICE.

RALPH W. CARNAHAN, OF CLEVELAND, OHIO, ASSIGNOR, BY MESNE ASSIGNMENTS, TO THE PARAMOUNT FIRE ALARM ENGINEERING COMPANY, OF CLEVELAND, OHIO, A CORPORATION OF OHIO.

COMBINATION FIRE AND POLICE ALARM AND TELEPHONE CALL BOX.

Application filed May 19, 1923. Serial No. 640,197.

This invention relates to a combined fire alarm and police call box provided with a telephone for the use of the police department, and has for its objects to produce a 5 box of this character in which the fire alarm mechanism only is accessible to the public, while the police alarm mechanism and telephone are accessible to the police department; the fire mechanism using a circuit to the fire 10 station separate from the police and telephone circuit and the police alarm mechanism and telephone both using the same circuit to police headquarters and being automatically thrown into or out of said circuit by the raising and 15 lowering of the telephone hook, a double make and break device being provided in the box and controlled by the movement of the hook for accomplishing the same.

The above and other objects may be attained by constructing the invention in the manner illustrated in the accompanying drawings, in which—

Figure 1 is a front elevation of a combined fire and police alarm and telephone call box 25 embodying the invention;

Fig. 2, an elevation of the same with the outer door opened, giving access to the telephone and police call box;

Fig. 3, an elevation of the mechanism 30 within the box;

Fig. 4, an enlarged side elevation of the police signal mechanism;

Fig. 5, a section through the same on the line 5—5, Fig. 3;

Fig. 6, a section on the line 6—6, Fig. 3;

Fig. 7, a vertical, sectional view through 35 one of the mercury make and break boxes;

Fig. 8, a perspective view of the double 40 make and break box controlling the telephone and police alarm signals;

Fig. 9, a vertical sectional view through the upper portion of the police alarm box;

Fig. 10, a section on the line 10—10, Fig. 9;

Fig. 11, a detail perspective view of the 45 operating gear in the police signal mechanism;

Fig. 12, a detail perspective view of the disk operated by the gear;

Fig. 13, a detail perspective view of the 50 ratchet through which the police signal mechanism is operated;

Fig. 14, a diagrammatic view of the wiring at the signal station and at the central station.

Similar numerals refer to similar parts 55 throughout the drawings.

The mechanism is contained within a metal box 1 arranged to be supported upon a suitable post or the like, and provided with the hinged door 2 having a compartment 3 60 formed therein and provided with the opening 4 through which extends the handle portion 5 of the operating lever of the fire alarm mechanism, a glass panel 6 covering the compartment, thereby making it necessary to break the glass in order to have access to the operating lever, as the door is normally held in the closed position by means of the lock 7.

With the parts in the position shown in Fig. 1, it will be seen that the public can 70 have access only to the operating lever of the fire alarm mechanism and this only by breaking the glass panel covering the same. The key to the lock 7 is in the possession of the police officer upon whose post the box is located.

When the door 2 is opened, as shown in Fig. 2, the policeman has access to the push button 8 which operates the police signal mechanism, the telephone transmitter 9 and the receiver 10 which hangs upon the hook 11, the weight thereon normally holding the hook down in the position shown in Fig. 2.

All of these parts are mounted upon or extended through the cover plate 12 which covers all of the fire and police signal mechanism and the telephone mechanism and is held in place as by the screws 13 which are extended into the partition walls 14 of the box.

The fire alarm signal mechanism is substantially the same as that disclosed in my copending application Serial No. 602,113, and is supported in the frame 15 which is mounted in the upper portion of the box in 95 rear of the plate 12.

The mechanism within the frame 15 is arranged to be operated by depressing the operating lever 5 and rotates the signal wheel 16, the circumferential surface of which is provided with groups of teeth 17 arranged in any desired combination to produce the signal impulses.

The teeth upon the signal wheel engage the depending tooth 18 of the lever 19, which is pivoted as at 20, the free end thereof being provided with an insulated knob 21 which engages the slidable rod 22 which carries the

movable contacts of the make and break device mounted in the insulated box 23.

As each of the several make and break devices in the box is of the same general construction, attention is here directed to Fig. 7, which shows a sectional view of one of the make and break devices.

The slideable rod 22 is slidably mounted through a suitable vertical bearing in the insulated box 23, within which the make and break device is contained, and is connected at its upper end to the yoke 24, the arms of which slide within vertical passages in the housing, the movable contacts 25 upon said arms being located within the chambers 26 formed in the insulated box.

Cups 27 are threaded into the lower ends of said chambers and carry the fixed contacts 28 to which the wires leading to the central station are connected, a suitable source of electrical energy being located in the circuit.

Each of the cups 27 contains mercury, and the movable contacts 25 are provided with the open tips 29 preferably formed of thin strips of suitable conducting material bent into the form shown in the drawings, and connected at their extremities to the cylindrical portions 25 of the movable contacts, thus leaving the central openings 29' through the tips, through which the mercury may flow when the movable contact members are in the normal position, in contact with the fixed contact members, as illustrated in Fig. 7.

The wires 30 lead from the fixed contact points of the make and break box 23 in the fire signal mechanism to the apparatus in the central fire station. Thus when the fire signal mechanism is operated through the depression of the operating lever 5, the signal wheel 16 will be rotated intermittently raising and lowering the yoke 24 to make and break the circuit to the central fire station at predetermined intervals, producing the proper impulses which operate the mechanism at the central station.

The police call mechanism is mounted in the lower portion of the box and housed between the side plates 31 and 32 and held in spaced relation as by the spacing bolts 33. The mechanism is arranged to be set in motion by the inward movement of the rack bar 34 provided with the push button 8.

The rack bar meshes with a winding member gear 35 which is rotatably mounted upon the hub 36 of the drum 37, rotatably mounted upon the shaft 38. The gear 35 is provided with the annular flange 39 extending into the socket 40 provided in the side plate 32 and a spiral spring 41 is connected at its outer end to the flange 39 and at its inner end to the shaft 38 for normally returning the gear and rack bar to the initial position.

The hub 36 of the drum 37 is provided with a disk 42 located within the annular flange 39 of the gear and provided with the shoulder

43 arranged to be engaged by the L-shaped pawl 44 which is pivoted as at 45 upon the gear 35.

A lever 46 is pivoted as at 47 upon a bracket mounted upon the side plate 32 and provided with a spring 48 tending to normally hold the lever out of engagement with the pawl 44. A finger 49 is fixed upon the side of the drum 37 for the purpose of engaging the lever 46 and rocking the same against the action of the spring 48 into engagement with the pawl 44.

A spring pressed pawl 50 is mounted in the cavity 51 of the drum and arranged to selectively engage each of the four ratchet teeth 52 upon the hub 53 of the gear 54 which is rotatably mounted upon the shaft 38. A block 55 is fixed upon the periphery of the drum 37.

A weight 56 is provided with the vertical ribs 57 upon its sides which are slidably mounted within the guide grooves 58 formed in the side plates. A tape or ribbon 59 is connected at one end to the drum 37 and passes under the pulley 60 which is mounted upon the weight, the other end of the tape being connected to the upper, rear, spacing post as at 61.

A stop 62 is fixed upon the inner face of the side plate 32 in position to be engaged by the outer end of the pawl 44 to disengage said pawl from the disk 42 when the gear 35 is rotated to the forward limit of its movement by the rack bar 34.

The gear 54 meshes with an idler gear 63 pivoted upon a stud 64 carried by the side plate 31. The idler 63 meshes with the pinion 65 upon the signal wheel shaft 66 which is journaled through the lower forward portions of the side plates 31 and 32, one end thereof extending through the plate 31, as shown at 67.

A notched disk 68 is fixed upon the shaft 66 and provided with the notch 69 arranged to be engaged by the weighted depending portion 70 of the stop lever 71, the upper end of which is located adjacent to the periphery of the drum 37, and arranged to be engaged by the block 55 upon said drum.

The lever 71 is pivoted intermediate its extremities as at 72 upon a stud 73 supported from the side plate 32. The gear 54 meshes with a pinion 74 fixed upon a countershaft 75, a gear 76 being also fixed upon said counter shaft and meshing with the pinion 77 upon the parallel shaft 78.

An escapement wheel 79 is fixed upon the shaft 78 and engaged by the palette 80 which is mounted upon the shaft 81. The palette acting upon the escapement wheel thus provides for a uniform operation of the gearing when the same is operated.

The signal wheel 82 is mounted upon the outer extremity of the shaft 66 and the periphery thereof is provided with groups of 130

projecting teeth 83 arranged in any desired combination to produce the proper signal impulses. The lever 84 is pivoted at one end as at 85 to the side plate 31 and is provided with the depending tooth 86 which normally rests upon the periphery of the signal wheel 82 and is arranged to be engaged by the groups of teeth upon the signal wheel 82 to intermittently raise and lower the lever 84 at predetermined times.

The insulated knob 87 is provided upon the end of the lever 84 to insulate the make and break mechanism and engages the sliding rod 22^a of the make and break device enclosed in the insulated box 23^a. The wires 88 from the make and break box 23^a are extended through the insulated wall 89 and are connected through the make and break box 23^b with the wires 90 which lead to the police headquarters.

The make and break box 23^c is preferably formed integral with the box 23^b. The jacks 91 and 92 for the attachment of the transmitter 9 and receiver 10 are connected by 25 the wires 93 with the line wires 90, through the make and break box 23^c.

The hook 11 of the telephone is fixed upon the rocker shaft 94 which is provided with a spring 95 for normally urging the hook 30 upward into the raised position. A lever 96 is fixed upon the rocker shaft 94 and is connected to the yokes 24^b and 24^c of the make and break devices 23^b and 23^c respectively, by means of the links 97.

When the receiver 10 is hanging upon the hook 11, the weight thereof is sufficient to hold the hook down, against the pressure of the spring 95, closing the circuit to the make and break device 23^b and opening the 40 circuit through the make and break device 23^c.

The line wires 90 lead to the police headquarters and as diagrammatically shown in Fig. 15, are connected up to the apparatus in the central office. A battery 98 or other suitable source of electrical energy is provided at the central office and connected as by the wire 99 with the telephone hook 100, the other side of the battery being connected 50 to one of the wires 90, the other wire 90 being connected to the punch register indicated at "To register 101."

When the hook 100 is in the normal or lowered position, it makes contact with the wire 55 102 which leads directly to the other side of the punch register and when the hook is raised by removing the receiver, it makes contact with the wire 103 which is connected to the transmitter 104 and receiver 105 and 60 leads to the same side of the punch register as the wire 102.

The door of the box normally remains closed and locked, as shown in Fig. 1, covering the police call mechanism and giving the 65 public access only to the operating lever of

the fire signal mechanism by breaking the glass 6.

The police officer upon whose post the box is located, carries a key to the lock 7 and by opening the door as shown in Fig. 2, he 70 has access to the push button 8 of the police signal mechanism and to the telephone which is connected to police headquarters.

When the telephone receiver 10 is hanging upon the hook 11, the hook is held in the lowered position, closing the circuit from the make and break device 23^a of the police signal mechanism to the central office through the make and break device 23^b, while the make and break device 23^c is in the open position, 80 breaking the circuit from the transmitter and receiver 9 and 10 respectively to the central office.

When the push button 8 is pushed inward to its limit, the rack bar 34 will rotate the gear 35 a trifle over one-fourth of a revolution, the pawl 44 upon the gear engaging the shoulder 43 of the disk 42 and rotating said disk with the gear.

The drum 37 being fixed to the hub 36 of the disk, will be rotated the same distance as the gear, the spring pressed pawl 50 thereof engaging one of the teeth 52 upon the hub 53 of the gear 54.

At this time, the pawl 44 upon the gear 35 will strike the stop 62, lifting said pawl out of engagement with the shoulder 43 upon the disk, the coil spring 41 throwing the gear back to the initial position, which, of course, moves the rack bar 34 outward to the initial 95 position.

As the drum 37 is rotated forward, the weight 56 will be raised by the tape 59, and as the parts reach the position above described, the block 55 upon the drum, will, at 105 the same time, strike the upper end of the lever 71, moving the lower weighted end 70 thereof out of engagement with the shoulder 69 of the disk 68.

The weight will then start to descend 110 slowly, moving the drum 37 back toward the initial position, the escapement mechanism causing the gearing to operate slowly and uniformly to rotate the signal wheel 82 the desired number of revolutions in the direction of the arrow shown thereon in Fig. 4, the teeth 83 thereof raising and lowering the lever 84 intermittently to produce the desired impulses through the make and break mechanism 23^a, operating the mechanism in 115 the central office to register the code signal from the police signal mechanism.

As the weight reaches the lower limit of its movement, the parts will be moved back to the initial position, the weighted end 70 of the lever 71, dropping into engagement with the shoulder 69 of the disk 68, stopping further movement of the gearing.

At the same time, the finger 49 upon the drum will strike the outer end of the lever 46, 130

throwing the inner end thereof into engagement with the outer extremity of the pawl 44 upon the gear 35, resetting said pawl in contact with the shoulder 43 of the disk 42.

5 It will be seen that after the rack bar 34 has been depressed to the full limit of its movement, the gear 35 is disengaged from the rest of the mechanism, permitting the rack bar to be moved without stopping or interfering with the operation of the signal mechanism which will continue to function until the signal number of the box has been transmitted to the central office and repeated the desired number of times for which the mechanism is set to operate.

10 After the police signal mechanism has been operated, the police officer may remove the receiver from the hook 11, when the spring 95 will immediately throw the hook into the raised position, breaking the circuit through the make and break box 23^b and closing the circuit from the transmitter and receiver 9 and 10 respectively to the central office, through the make and break box 23^c, permitting the telephone to be used to talk from the box to the central station.

15 This operation of the police signal mechanism and telephone does not in any way interfere with the circuit from the fire alarm mechanism for the reason that the fire alarm employs a circuit separate from the police and telephone circuit, and permits of a fire alarm being sent in at the same time the policeman is using the police signal mechanism.

35 I claim:—

1. In a signal transmitter, transmitting mechanism comprising a rotatable drum having means associated therewith whereby when the drum is rotated in one direction it stores energy to transmit the signal and gradually returns to its normal position during transmission of the signal, a disk fixed to the drum and provided with a shoulder, a rotatable winding member, an L-shaped pawl pivoted upon the winding member and adapted to engage the shoulder upon said disk, a finger on said drum, a spring pressed lever adapted to be struck by said finger to throw the pawl into engagement with the shoulder of the disk, and a stop for disengaging the pawl from the disk when the winding member is rotated to the limit of its winding movement.
2. In a signal transmitter, transmitting mechanism comprising a rotatable drum having means associated therewith whereby

when the drum is rotated in one direction it stores energy to transmit the signal and gradually returns to its normal position during transmission of the signal, a disk fixed to the drum and provided with a shoulder, a rotatable winding gear, a rack for rotating the gear, an L-shaped pawl pivoted upon the gear and adapted to engage the shoulder upon said disk, a finger on said drum, a spring pressed lever adapted to be struck by said finger to throw the pawl into engagement with the shoulder of the disk, and a stop for disengaging the pawl from the disk when the gear is rotated to the limit of its winding movement.

3. In a signal transmitter, transmitting mechanism comprising a rotatable drum having means associated therewith whereby when the drum is rotated in one direction it stores energy to transmit the signal and gradually returns to its normal position during transmission of the signal, a disk provided with a notch associated with the transmitting mechanism, a stop lever having a weighted end adapted to engage the notch in the disk, and a block upon the drum adapted to disengage the stop lever from the notch in the disk when the drum is rotated to the limit of its energy storing movement.

4. In a signal transmitter, transmitting mechanism comprising a rotatable drum having means associated therewith whereby when the drum is rotated in one direction it stores energy to transmit the signal and gradually returns to its normal position during transmission of the signal, a disk fixed to the drum and provided with a shoulder, a rotatable winding member, an L-shaped pawl pivoted upon the winding member and adapted to engage the shoulder upon said disk, a finger on said drum, a spring pressed lever adapted to be struck by said finger to throw the pawl into engagement with the shoulder of the disk, a stop for disengaging the pawl from the disk when the winding member is rotated to the limit of its winding movement, a disk provided with a notch associated with the transmitting mechanism, a stop lever having a weighted end adapted to engage the notch in the disk, and a block upon the drum adapted to disengage the stop lever from the notch in the disk when the drum is rotated to the limit of its energy storing movement.

5. In testimony that I claim the above, I have hereunto subscribed my name.

RALPH W. CARNAHAN.
